WORK SUPPORT AND LAST

Filed Aug. 13, 1917

INVENTOR:
Albert Latham

Patented Mar. 13, 1923.

UNITED STATES PATENT OFFICE.

ALBERT LATHAM, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WORK SUPPORT AND LAST.

Application filed August 13, 1917. Serial No. 185,952.

To all whom it may concern:

Be it known that I, ALBERT LATHAM, a citizen of the United States, residing at Beverly, in the county of Essex and State of Massachusetts, have invented certain Improvements in Work Supports and Lasts, of which the following description, in connection with the accompanying drawings, is a specification, like reference characters 10 on the drawings indicating like parts in the several figures.

This invention relates to work supports and in particular to work supports in connection with lasts of special types, particularly hinge and separable lasts.

Lasts of the former type are frequently made with a positive lock holding the forepart and heel part in extended position. This lock must be thrown before the last 20 can be collapsed and removed from the shoe, and access to it is difficult when the last is in the shoe.

Lasts of the latter type are sometimes so constructed that the heel part can be removed from the forepart, this being done preferably while the forepart is in the shoe. The removal of the heel part of such a last is, however, troublesome, owing to the cramped situation in which the operator is obliged to 30 work. Moreover, a shoe with the forepart of a last remaining in it is hard to handle in later operations, and the removal of the forepart itself has been attended with some difficulty heretofore owing to lack of appropriate means for handling it.

It is the general object of my invention to provide simple, cheap and efficient means for handling lasts of the types mentioned.

An important feature of the invention 40 consists in a work support adapted to support a separable last and to unlock the bonding mechanism thereof to permit the removal of the heel part while the forepart remains in the shoe. The last illustrated is not only 45 separable but hinged and my novel work support co-operates with the bonding mechanism in such manner as to make possible the collapse of the last.

Another feature of the invention consists 50 in a work support having means for supporting a detached last forepart. This feature facilitates the handling of the shoe after the heel part has been removed, and simplifies

the operation of removing the forepart itself from the shoe.

These and other features of the invention comprising various arrangements and combinations of parts, will be understood from the following description of a preferred embodiment of the invention in connection 60 with the separable hinge last shown in my copending application, Serial No. 53,959, filed Oct. 4, 1915. The particular work supports and last shown are selected only for purposes of illustration and the scope of 65 the appended claims is not to be limited to the specific apparatus described.

In the drawings:

Fig. 1 shows a side elevation of a last and a work support.

Fig. 2 shows the last in collapsed position.

Fig. 3 shows the last forepart on its support.

Fig. 4 is a perspective of the forepart support.

Fig. 5 shows the head of the support shown in Figs. 1 or 2.

Fig. 6 shows the rear portion of the last bonding mechanism; and

Fig. 7 shows the fore portion of this bonding mechanism.

The last shown will be first described.

A forepart 10 of the last has mounted in it three headed pins 11. The forepart is recessed at 12 and still deeper recessed at 13 and the pins 11 have their heads protecting just beyond the backs of these recesses. The lower part of the forepart is cut off at an angle to the back of the lower recess at 14. The heel part 15 has its front surface 90 beveled straight across on the same slant as the surface 14 of the forepart. It has mounted upon its front surface a plate 16 which forms the rear member of the hinge. The front member of the hinge 17 is hinged to the plate at its lower end at 18 and is provided with two downturned notches 19 at its lower end and a recurved portion 20 at its upper end having a downturned notch 21. These three notches 19 and 21 are so arranged as to register exactly with the three headed pins 11 so that the plate 17 can be placed in contact with the surface 12 and then slipped downward to engage the heads of the pins 11 in the notches 19 and 21.

The plate 17 has mounted upon its rear

face a loop 22. The plate 16 has pivotally mounted at its upper end a bail 23 which passes inside the loop 22. Near the lower end of the loop 22 a projection 24 is formed 5 on the back of the plate 17. The bail 23 is normally held elevated by the spring 25. The plate 16 has at its lower end a struck up tongue 26. When the bail 23 is pushed downward its outer end will hook under the 10 projection 24 and hold the plate 17 substantially parallel to the plate 16. With the parts in this position the last can be assembled, the plate 17 being placed on the surface 12 and slipped downward over the pins 15 11. Slight pressure upon the heel part of the last will then pull the end of the bail 23 out from under the projection 24 and the bail 23 will rise to the upper end of the loop 22 as the heel part settles back into extended 20 position, the plates 17 and 16 being thereby separated into the position shown in Fig. 1. The bail 23 settles against the upper end of the loop 22 and acts as a strut to lock the last in extended position. At the same time 25 the tongue 26 swings forward under the two lower pins 11 which are thus grasped firmly between the notches 19 and the tongue 26. The lower front surface of the heel part fits snugly under the surface 14. The 30 last may be collapsed by pressing down the bail 23 until it passes the perpendicular to the plate 17, after which the heel part can be turned around the pivot 18, the bail 23 sliding downward over and under the projection 24 which it engages frictionally, the friction being sufficient to keep the heel part from falling back into extended position by its own weight, although the angle between the lower surface of the projection 24 35 and the plate 17 can be so filed out as to enable the heel part to fall into extended position under any desired extra pressure.

The work support 30 comprises a base cored out to receive the vertically sliding 45 jack pin 32. This pin is resiliently supported on the spring 34 which rests on the screw 36. A collar 38 is mounted on a reduced portion 40 of the head of the support and may rotate thereon or be pinned as shown. 50 The collar has an upturned finger 42.

The work support 44 (Figs. 3 and 4) comprises a base and a standard 46 containing three slots 48 constructed to engage and hold the three headed studs 11. The room 55 occupied by the supporting member is small, and substantially the entire heel portion of the insole is left uncovered by it, and is therefore accessible to mechanism designed to co-operate with this part of the shoe.

60 The last locked in extended position with the shoe on it may be placed on the jack pin 32, as shown in Fig. 1. The shoe will thus be supported in the ordinary way. When it is desired to remove the heel part 65 from the shoe the last will be depressed by

the operator, telescoping the pin 32 into the base. The member 23 will descend against the finger 42, and will be pressed upward, as shown in dotted lines in Fig. 2. This unlocks the bonding mechanism between the heel part and forepart, and permits the removal of the heel part from the shoe. In Fig. 2 the lower dotted lines 70 show the initial collapsing movement, and the full lines show the last fully collapsed, 75 after the pin 32 has raised it from the finger 42.

The forepart, carrying the shoe may now be mounted upon the support 44, the notches 48 engaging the headed pins 11 in the same 80 way as the plate 17. The support will hold the shoe during subsequent operations, permitting cooperation with the heel end of the insole by any mechanism desired, or if it is desired to take the forepart from the 85 shoe, it will hold the forepart firmly against the operator's pull in removing the shoe.

What I claim as new and desire to secure by United States Letters Patent is:

1. In combination with a last forepart 90 having bonding means constructed and arranged to co-operate with a complementary bonding means on a heel part to permit the removal of the heel part while the last is in the shoe, a work support having means for 95 engaging and co-operating with the forepart while still in the shoe after the heel part has been removed to support the shoe for further shoemaking operations.

2. In combination with a last forepart, 100 having bonding means for attachment to a heel part, a work support constructed and arranged to engage said bonding means to support the forepart and permit co-operation between the rear end of the insole and 105 a shoe treating instrumentality.

3. In combination with a last forepart having bonding means constructed and arranged to engage a heel part, a work support having means constructed and arranged 110 to co-operate with said bonding means to support said forepart.

4. In combination with a work support having interlocking members, a last forepart having corresponding interlocking 115 members to cooperate with the first-mentioned interlocking members to support the forepart, said forepart being also arranged to cooperate with interlocking members on a last heel part, said last-mentioned interlocking 120 members being identical with said work support interlocking members.

5. In combination with a last forepart having headed pins arranged to cooperate with corresponding slots on a heel part in 125 order to hold said forepart in extended position relatively to said heel part, a work support having similar slots arranged to engage said pins to support the forepart.

6. A last forepart and a work support, 130

the said objects being provided with interlocking mechanism comprising a headed pin on one of said objects and a corresponding slot upon the other of said objects to enable 5 the work support to support the forepart, said interlocking member on the forepart being also arranged to cooperate with an

interlocking member on a heel part similar to the interlocking member on the work support to hold the forepart in extended relation relatively to the heel part. 10

In testimony whereof I have signed my name to this specification.

ALBERT LATHAM.
